[57] CLAIM

The ornamental design for tethered holder for cylindrical articles, as shown and described.

DESCRIPTION

FIG. 1 is a perspective view of a tethered holder for cylindrical articles showing my new design, the broken line showing of a cylindrical article being for illustrative purposes only and forming no part of the claimed design;

FIG. 2 is a front elevational view;

FIG. 3 is a right side elevational view;

FIG. 4 is a rear elevational view;

FIG. 5 is a top plan view; and

FIG. 6 is a bottom plan view.

FIG. 1

FIG. 2

FIG. 3

FIG. 4

FIG. 5

FIG. 6
